UNITED STATES PATENT OFFICE.

COTTER STRAWN CHALFANT, OF CHICAGO, ILLINOIS.

SPARK ARRESTER FOR LOCOMOTIVES.

1,408,075.

Specification of Letters Patent. Patented Feb. 28, 1922.

Application filed November 26, 1920. Serial No. 426,643.

To all whom it may concern:

Be it known that I, COTTER STRAWN CHALFANT, a citizen of the United States, and a resident of Chicago, in the county of Cook and State of Illinois, have invented a new and useful Improvement in Spark Arresters for Locomotives, of which the following is a full, clear, and exact description.

My invention relates to improvements in 10 spark arresters for locomotives, and it consists in the combination, constructions and arrangements herein described and claimed.

An object of my invention is to provide 15 a device for separating the sparks, cinders, and other unconsumed substances from the gases of combustion in a locomotive engine and for returning the same to the furnace of the engine for further consumption, whereby the efficiency of the engine is increased and loss resulting from the igniting 20 of adjacent property by sparks from the engine is obviated.

A further object of my invention is to 25 provide a device of the type described that can be operatively applied to a locomotive engine of conventional construction without interfering in any way with the functioning of the relatively moving parts ordinarily provided therein.

30 A further object of my invention is to provide a device of the type described that is relatively simple in construction and operation, thoroughly effective for the purpose intended, and practical commercially.

35 Other objects and advantages will appear in the following specification, and the novel features of the invention will be particularly pointed out in the appended claim.

40 My invention is illustrated in the accompanying drawings, forming part of this application, in which—

Figure 1 is a side elevation showing the preferred form of the device operatively applied to a locomotive engine, portions being broken away and other portions shown in section,

Figure 2 is a front view of the mechanism shown in Figure 1,

Figure 3 is a side elevation, partly in section, of a fragmentary portion of a locomotive engine, showing a modified form of the device applied thereto, and

Figure 4 is a front view of the locomotive engine illustrated in Figure 3, showing the modified form of the device operatively applied.

It is well known that a large percentage of the fuel fed into a furnace of a locomotive engine is ejected through the smoke stack without being entirely consumed and that therefore a distinct gain in efficiency of the engine will be attained by providing means for separating the unconsumed portions of the fuel from the gases of combustion and for returning such unconsumed portions to the furnace of the engine. In addition the loss resulting from fires occasioned by the igniting of adjacent properties by sparks ejected through the smoke stack of an engine is comparatively great. Such a loss will be obviated when adequate means for preventing ejection of sparks through the smoke stack are provided.

Devices of which I am aware for obtaining the results set forth above, while no doubt theoretically operative, have been found unsatisfactory in actual service in that such devices involve complicated structures, or interfere with the ordinary functioning of operating parts of the engine. When my device is applied to a locomotive engine, the results sought are obtained without interfering in any way with the functioning of the parts of the engine and without the necessity of providing a complicated or costly structure, and without expensive changes in the ordinary structure of the locomotive engine to which applied being required.

In carrying out my invention I may make use of a locomotive engine of the type intended for passenger service, such as is indicated generally at 1 in Figure 1 of the drawings. The engine is provided with the usual shell 2 having fitted therein a head 4 to divide the interior thereof into a water chamber 3 and an outlet chamber 5. The gases of combustion from a fire box, not shown, that is positioned in the rear part of the engine pass through tubes 6 that are disposed in the water chamber 3 and open through the head 4 into the outlet chamber 5. A baffle plate 7 positioned within the outlet chamber 5 deflects the gases of combus-

tion passing from the tube 6 downwardly in the outlet chamber 5. The shell 2 is formed with its front end open, as at 8 and is also provided with a smoke stack 9.

5 The parts described so far are ordinary in construction and form no part of my invention except in so far as they cooperate with the parts about to be described.

A plate 10 is fitted within the outlet chamber 5 substantially parallel with the head 4 and to the rear of the smoke stack 9 as clearly shown in the drawings. The plate 10 is provided with a central opening 11 normally closed by a cover plate 12 secured thereto in any suitable manner as by means of bolts 13. The gases of combustion deflected downwardly by the baffle plate 7 pass through an opening 14 into a passage 15 between the exterior wall of the shell 2 and a saddle or cylinder block 16. From the passage 15 the gases are conducted through an opening 16' into the outlet chamber 5 adjacent the front end of the engine. A continuous spiral channel 17 within the outlet chamber 5 is provided by securing an inwardly extending spirally directed fin 18 to the inner wall of the shell 2 in any suitable manner as by welding the outer edge of the fin to the shell. One end of the channel 17 communicates with the opening 16' while the other end thereof communicates with a tubular member 20 at a point adjacent the throat of the smoke stack 9. The tubular member 20 passes through the shell 2 at 19 as best seen in Figure 2 and extends to the fire box, not shown.

From the foregoing description of the various parts of the device, the operation thereof may be readily understood. The 40 gases of combustion passing through the tubes 6 entrain cinders, sparks and partly consumed fuel substances. Such substances pass with the gases along the passage 15 and into the spiral channel 17. The exhaust 45 pipe 21 from the power cylinders of the engine opens into the channel 17 at this point and forces the gases of combustion and the unconsumed substances along the spiral channel 17 at a high velocity and under the 50 influence of a centrifugal force. Air will be drawn from the atmosphere through the opening 8 as indicated by the arrows in Figure 1 and will entrain the light gases of combustion from the channel 17, conducting the 55 same through the smoke stack 9 to the atmosphere. The cinders, sparks and other unconsumed particles will remain in the channel 17 on account of their relatively great weight and will pass therefrom into 60 the tubular member 20 and thence to the furnace of the engine. It will thus be seen that the operation described will be repeated until all the solid substances fed into the furnace are reduced to a gaseous state.

Referring now to Figures 3 and 4, I show 65 a modified form of the device applied to an engine of the type designed primarily for freight service. In the drawings 30 denotes the shell which has fitted therein a head 31 to provide a water chamber 32 and an outlet chamber 33. The gases of combustion pass through tubes 40 disposed in the water chamber 32 that open through the head 31 into an outlet chamber 33 and are drawn 70 into a conduit 35 having a bell end 36 positioned directly above an exhaust pipe 34 from the power cylinders. The conduit 35 is spirally directed as shown and passes through a plate 37 that is fitted within the outlet chamber 33 parallel with the head 31. After passing through the plate 37 the conduit 35 is continued as a spirally directed channel 38 that is semi-cylindrical in cross section and is arranged to communicate with a tubular member 39 at a point adjacent to 80 the front end of the engine and near the throat of the smoke stack 41. The tubular member 39 passes through the shell 30 and extends to a furnace, not shown, of the engine. 90

The operation of the modified form of the device is similar to that of the preferred form of the same device as hereinbefore set forth. The gases of combustion together with the entrained cinders, sparks, and other 95 substances not entirely consumed in the furnace pass from the tubes 40 and on account of the suction thereon created by the exhausting of steam from the power cylinders into the tube 36 are drawn into the latter 100 and pass along the channel 38. It will be noted that the convolution of the spiral channel adjacent the front end of the engine has a portion of its length secured to the shell 30 at the rear of the smoke stack 41 105 while the remaining portion thereof is secured to the shell 30 at the opposite side of the smoke stack. Consequently the light gases of combustion will pass through the smoke stack while the heavier cinders, 110 sparks, and other substances will remain within the channel 38 and will pass therefrom into the tubular member 39 and thence be returned to the furnace of the engine.

The device is thoroughly effective for the 115 purpose intended and can be installed in any engine of standard construction at slight cost and without interfering in any way with the normal operation thereof. It is therefore obvious that a great saving in fuel will 120 result and that the efficiency of the engine will be greatly increased.

I claim:

The combination with an outlet chamber at the front end of a locomotive engine, said 125 outlet chamber being provided with a stack and an inlet for a pressure fluid, of a spiral conduit arranged in the outlet chamber with

one open end thereof positioned directly above the inlet for the pressure fluid and with the other open end thereof positioned directly beneath and adjacent to the stack 5 orifice, means for conducting the gases of combustion from the fire tubes with the entrained unconsumed solid substances into position to enter the conduit at its first named end, and a declined conduit communicating with the spiral conduit at its 10 last named end and leading to the fire box of the engine for conducting the unconsumed solid substances to the latter.

COTTER STRAWN CHALFANT.
